MEANS FOR FORMING WINDOWED APERTURES

Edward T. Jaeger, Rupert Loeffler, Jr., and Louis Bischoff, New York, N. Y., assignors to Oneida Paper Products, Inc., New York, N. Y., a corporation of New York

Application March 23, 1939, Serial No. 263,648

8 Claims. (Cl. 164—89)

This invention relates to apparatus and means for the formation of sheets, bags or containers of various kinds, and particularly relates to apparatus for forming transparent windows or other openings in a continuous web of material, such web being thereafter used for the formation of the aforementioned articles.

In the formation of transparent openings in a continuous web, it is necessary first to exercise a portion of the material forming the opening and thereafter to cover such opening with a patch of transparent material including transparent regenerated cellulose material such as Cellophane, Sylph-wrap or the like.

Where a continuous web of sheet material such as paper or other substance is to be thus provided with a series of transparent windows or openings, the web to be thereafter cut up and formed as may be desired, there has heretofore been difficulty in providing means for cutting the opening without interfering with the movement of the web of sheet material or without tearing any portion of such web. Various means such as, for instance, halting the progress of the web at the moment the cut is made or providing a rotatable cutting means wherein the cutting edge constantly travels at the same speed as the web have been used.

Where it is necessary to stop the movement of the web to permit the cutting operation to take place, then extreme difficulty is experienced in obtaining proper register of the edges of the sheets in relation to the cut-out or perforation to be made. The necessary sudden cessation of movement of the web and the sudden recurrence of movement thereof often tends to wrinkle and distort the sheet so that the cut-out or perforation may be irregular or the sheet itself may be torn or distorted.

In the case of a machine having a cutting knife in a rotating cylinder, it may be necessary to use the same size slot on a bag or sheet of different lengths. This cannot be done unless the rotating cutting knife cylinder is changed to the required diameter for each length of bag or sheet. Therefore, no unanticipated sizes could be quickly manufactured owing to the necessity for first making a cutting cylinder having a circumference exactly equal to the new sizes desired.

Objects of this invention therefore are to provide in an apparatus for forming an opening or a transparent window in sheet material, means whereby a continuous web of such sheet material may be cut, perforated or slotted with openings of predetermined size and in predetermined re-

lation to each other without any variation in the speed or movement of the web of sheet material.

Further objects of this invention are to provide means for varying the distance between cut-outs, perforations or slots formed in a continuous web of sheet material without the necessity for any change in the mechanism forming the cut-outs, without any requirement for additional special or multiple parts for such mechanism (such parts being substantial duplicates for each other except as to size) and without the necessity for continually stopping, altering and adjusting the machine.

Heretofore it has been extremely difficult in the manufacture of transparent openings in sheet material to perform the operation of cutting the opening and affixing the transparent material at the opening in a single continuous automatic operation. Difficulties have arisen in registering the cut-out portion exactly with the transparent material to be applied over such cut-out. Further difficulties have arisen owing to the fact that the transparent material to be applied over the opening was to be applied in patches, that is, in cut-off lengths; while the web upon which such patches were to be applied was a continuous moving sheet.

Accordingly, further objects of this invention are to provide apparatus by means of which the continuously moving web may, after it has been slotted or perforated or after the cut has been performed, have such cut-out covered by a transparent patch without any interruption of the operation or without any necessity for manual manipulation.

Still further objects of this invention are so to arrange the mechanism that, instead of the necessity for applying a series of patches upon the material surrounding the cut-out or perforation, the material forming the transparent window may be supplied to the machine in a continuous roll, the machine cutting patches from such continuous roll and causing such patches to adhere to the material surrounding the cut-out in a fully automatic operation.

Another object of this invention is so to construct the mechanism which applies the transparent patch to the cut-out as to provide simplified means for quickly changing either the length of the patch to be applied or the distance between the patches applied in accordance with any variations in the size of slot or cut-out and/or the distance between such cut-outs.

Other objects of this invention are to eliminate the changing of dies or knives, where the same

slot is to be used in varying sizes of bags or sheets, by a simplified readily adjustable means for changing the stroke of the cutting means.

Still further objects and uses of this invention will, in part be apparent, and in part, be pointed out in the following description taken in connection with the drawings, in which:

Figure 1 is a side elevational view of the transparent window-forming mechanism comprising this invention.

Figure 2 is a corresponding side elevational view of the mechanism of Figure 1 taken on the opposite side of the mechanism.

Figure 2a corresponds to Figure 2 and is a schematic perspective representation of the various parts of the mechanism.

Figure 3 is a top elevational view of the mechanism of Figure 2 taken along the line 3—3 of Figure 2, and looking in the direction of the arrows.

Figure 4 is a top elevational view of the mechanism of Figure 2 taken along the line 4—4 of Figure 2 and looking in the direction of the arrows.

Figure 28 is a sectional elevation taken along 28—28 of Figure 1.

Figure 29 is a sectional elevation taken along line 29—29 of Figure 1.

Figure 30 is an elevational view taken along 30—30 of Figure 1.

Figure 31 is a cross sectional view taken along 31—31 of Figure 8.

Figure 32 is a cross sectional view taken along 32—32 of Figure 10.

Figure 33 illustrates a continuous web having a transparent window formed therein.

Figure 33a shows said web cut and folded to produce the bag of Figure 34.

Referring now to Figures 1, 2 and 2a, the main roll of sheet material 50, in which transparent windows are to be formed, is mounted upon rollers 51 which in turn are mounted in the bifurcated member 52 and is free to rotate therein.

The sheet material or web 53 may be threaded through the machine in various different ways. The machine here illustrated provides for at least three operations, to wit: The printing of the main

35 35 operations, the perforation or cutting out of an opening therein thereof, and the application of a transparent sheet or patch at the perforated or cut-out point. These operations may be performed in any desired order, or certain of these 40 operations may be omitted. The order in which these operations are performed is determined by the manner in which the paper or sheet 53 taken from the roll 50 is threaded through the various portions of the machine.

45 It should be noted that, in the description hereinafter set forth, the printing rolls or mechanism are not an essential part of the machine; but are shown schematically in their relation to the machine which comprises the invention 50 herein.

In many cases, it is desirable merely to effect the cut-out, apply the transparent patch thereon and reserve any printing operation for any later manufacturing operation that may be necessary.

55 55 In the event that it is so desired merely to form the window without any printing matter whatsoever upon the sheet, itself, the web 53 is threaded along the path A (indicated by dotted lines) past the idling roller 54 whereby the direction of the moving sheet is changed. The

60 60 direction of the moving sheet is again changed by the idling roller 55 directly above the roller 54 and the web 53 then is moved past the feed roller 56 whence it travels over the idler 57 and into and through the punching mechanism 58.

Owing to the fact that the web or sheet 53 must pass through various different processes and apparatus in its passage through the machine itself, it is necessary especially where the web is not of great tensile strength to provide feed rollers giving it a forward impetus in its various movements, rather than to rely merely on the pull at the end of the web as it emerges 70 70 from the machine. For this purpose, the roller 75 75

56 is not an idling roller but a driven one as hereinafter described.

The machine itself is driven by means of the belt 53 which is connected with any desired motive power and which drives the pulley 60. The pulley 60 in turn drives the shaft 61 which in turn causes the pinion 62 to rotate thus driving the gear 63 which through the bevel gears 64 and 65 causes the shaft 66 to rotate in its bearings 67, 68, friction being greatly reduced by the thrust bearings 68, 68.

The bevel gear 69 at the opposite end of the shaft 66 meshes with the bevel gear 70 which thus causes the shaft 71 to rotate. The rotation of shaft 71 drives the change gear wheel 72 which in turn drives the idling gear wheel 73 which drives the gear wheel 74 whereby the gear wheel 75 is rotated, thereby rotating the shaft 76 and thus causing the rubber roller 77 to rotate. The roller 56 is mounted on the shaft 78 (see also Figure 1) which is rotated by the gear wheel 74.

Thus the feed roller 56 and the corresponding roller 77 capture the web of sheet material 53 between them and cause the web to move on towards the punching mechanism 58.

Where printing rolls are to be used, gear 79 driven by shaft 78 drives idler 80 which is free to turn on shaft 71. Sprocket 500 attached to gear 80 drives the printing rolls 501 through the sprocket chain 502. It will thus be clear that any change in the speed of the feed rolls will result in a change of speed of the printing rolls.

Where it is necessary to thread the web of sheet material 53 through the rollers 56 and 77, that is through the gap 81 (Figure 18) between them, there is provided at 82 (Figures 2 and 18) means for raising the rubber roller 77 away from the roller 56 thus widening the gap and permitting the ready insertion and threading through of the web 53. Such means for raising the rubber roller 77 comprises slideable mountings 83, 83 (Figures 18, 19 and 20) for the shaft 76. Such slideable mountings 83 are captured within the stationary member 84 (Figures 19 and 20) said stationary member 84 having slots 85, 85 within which the slideable mounting 83 may travel.

The slideable mounting does not rest directly upon the interior base 86 of the stationary member 84 but a coil spring 87 under compression is provided between the base 86 and the slideable mounting 83. The upper end of the slideable mounting 83 is provided with a series of bevel studs 88, 88 separated from each other by spaces approximately equal to or greater than their diameter. As seen in Figures 19 and 20, it will be obvious that the depression of the slideable mounting 83 will cause the rubber roller 77 to more closely approach the feed roller 56 while a raising of the slideable mounting 83, as seen in Figure 20, will correspondingly cause the gap 81 between the rubber roller 77 and the roller 56 to increase and provide sufficient space for the threading of the paper. Since the spring 87 is a compression spring, in its normal condition, it would tend to maintain the slideable member 83 at or near the uppermost part of the member 84 thus tending, when the pressure on such spring is released, to drive the rollers 77 and 56 apart. The compression spring 87 is maintained under compression, however, by the fact that bevel studs 89 mounted upon the rotatable member 90 register end to end and press against the bevel studs 88 of the slideable mounting 83 (as in Figure 19). When the rotatable member 90 is

turned upon its shaft 91 so that the upper bevel studs 89 no longer register end to end with the roller bevel studs 88 but instead register with the spaces between them, then the slideable mounting 83 is forced up by compression spring 87, a distance equal to the axial length of one set of bevel studs until the studs bear against the base of the opposite member, and the rollers 77 and 56 are separated. In order to facilitate the rotation of the shaft 91 and the consequent rotation of the rotatable member 90 and its associated bevel studs 89, a handle 92 is attached to the rotatable shaft 91 by means of the collar 93.

Since the shaft 76 extends from one side to the other of the machine, the mountings 82 on each side of the machine as seen especially in Figure 18 are exactly similar and the turning of the two corresponding handles 92 simultaneously will cause the shaft 76 to rise evenly and in the same plane and will thus cause the rubber roller 77 to rise.

In order to insure that the handles 92, 92 on either side of the shaft 76 will be rotated simultaneously so that the shaft will rise evenly and in the same plane, a link 94 is mounted between the two handles 92, 92 and is hingedly connected to each handle by pivots 95, 95. It will thus be obvious that rotation of either handle 92 will through the link 94 communicate the same motion to the corresponding handle at the opposite end and will thus cause both ends of the shaft 76 to rise simultaneously. Likewise the provision of the link 94 makes it possible to cause the shaft to rise by manipulating either of the handles 92 or even by grasping any portion of the link 94 causing it to move in the desired direction.

After the paper or web is properly threaded through the gap 81 (Figure 20), then the handles 92 or the link 94 may be rotated or pushed in a direction opposite to that in which they had previously been moved and the shaft 76 and its rubber rollers 77 will thereby be depressed and will engage the web 53 between the rollers 77 and 56. The bevel studs 88 and 89 are so arranged that lateral pressure of a stud on one member against a stud on an adjacent member will cause the stud on the movable member 83 to slide down, thus causing the movable member 83 to slide down and thus causing the studs to register with each other end to end rather than side to side. The beveling of the studs must therefore be at such angle or curvature as to permit this sliding arrangement to take place.

The rollers 56 and 77 thus feed the paper forward over the idling roller 57 into the punching mechanism 58.

Although we have here described in detail one way of separating the feed rollers to permit threading of the web through the machine, it of course will be clear that any other suitable means may be used which will separate such rollers for threading purposes and then bring them together to perform the feeding operation.

The punching mechanism (see Figures 2, 5 and 8) comprises a movable platform 96 which is mounted at either lateral edge thereof upon free rollers 97 (see also Figures 6 and 7) which in turn are mounted in a truck 98. The free rollers 97 thus carry the movable platform 96 upon the upper portions of the rim thereof, the lower portions of the rollers 97 riding in the track 99 which is attached by the bracket 100 to the frame 101. A rack 102 is also mounted beneath the movable platform along the lateral ends thereof, said rack being mounted imme-

diately above a corresponding rack 103 which is mounted in the bracket 100. A pinion 104 is rotatably enmeshed between the two racks 102 and 103 and thus assures that the movable platform 96 will at all times register accurately with the mounting bracket 100, the free rollers 97 being provided merely for the purpose of reducing friction.

The movable platform 96 carries, securely attached thereto, the vertically arranged arms 105 and 106 (see Fig. 8). V-shaped tracks or slots 107—108 are mounted in the lateral edges of the upper ends of each of the arms 105 and 106 (see Figures 8 and 9). The punching plate 109, Figure 8, is mounted upon a slidable member 110, the ends of which 111, 111 (see also Fig. 9) are shaped to ride in the tracks 107 and 108. Upward and downward reciprocating motion of the slidable member 110 in the tracks 107 will obviously result in corresponding upward and downward motion of the punching plate 109. Such reciprocating motion is accomplished in the following manner: Brackets 112, 112 are securely attached to the upper end of the arm 106, 106. Shaft 113 rotates in a manner hereinafter described in the bearings 114, 114 which are carried by the brackets 112, 112; cam 115 is mounted at one end of shaft 113 and thus rotates therewith. A link 116 is rotatably attached to the cam 115 by the eye 117. The opposite end of the link 116 is rotatably attached by means of the yoke 118 to the slidable member 110. A slot 119 permits the link 116 to pass through the upper covering 120 of the chamber 121 in which the slidable member rises and falls.

It will now be obvious that rotation of the shaft 113 and the corresponding rotation of the cam 115 will, through the rotatable eye 117, cause the link 116 to reciprocate vertically and thereby cause the slidable member 110 to correspondingly move up and down thus causing the punching plate 109 to operate.

A counter-weight 122 may be mounted on the shaft 113 to compensate for the weight of the sliding member 110 and its associated punching plate and to avoid any vibration or friction which may occur due to the weight on the cam 115.

An opening 123 is formed in the movable platform 96 and a plate 124 is secured to said platform 96 surrounding said opening 123 and having also an opening 125 surrounded by the female die 126 which exactly matches the punching plate 109. It will now be obvious that when the moving web 53 passes beneath the punching plate 109 and over the die 126 a perforation will be made in the web 53 by the pressing down of the punching plate 109 into the die 126, owing to the rotation of the cam 115, and the material 127 thereby excised will be thrown down into the funnel 128.

In order to ensure that the material 127 will be pressed down and away from the cutting edges of the die 126, small plungers 129, 129 may be mounted on the under surface of the punching plate 109, the ends of the plungers being forced to project beyond the face of the punching plate by the springs 130. By this means, the plungers 129 will press against the center portion of the material 127 to be excised but nevertheless the springs 130 will permit such pressure to be a yielding and light pressure which will not tear the paper web 53; but when the material 127 has been cut from the web 53 by the operation of the punching plate 109 and the die 126, the compression of the springs 130 will permit the

plungers 129 to be extruded from the face of the punching plate 109 and thus force the material 127 away from the edges of the die 126 so that the cutting edges will be free to receive the punching plate when the next perforation is made.

The web of sheet material 53 may be held perfectly flat, during the cutting operation and during all of the time that the punching plate 109 is beyond the surface of web 53, by means of a plate 131 which may be provided near the under face of the punching plate 109; said plate 131 having an orifice 132 which is slightly larger in each dimension than the corresponding dimension of the punching plate. The said plate is mounted upon the slidable mounting 110 by means of the springs 133. When the slidable member 110 is forced downwardly by the action of the cam 115, the plate 131 will come in contact with the web 53 either simultaneously with or before the face of the punching plate 109 and will thereby press the paper against the upper surface of the die 126 and thus prevent any breaking, tearing or distortion which may be caused by the subsequent entry of the punching plate 109 through the paper 53 and into the die 126. When the slidable member 110 thereafter begins to rise and withdraw punching plate 109, the plate 131 will nevertheless remain in contact with the web 53, pressing it against the outer surface of the die 126 at least until the punching plate 109 is fully withdrawn from the die 126 and from the outer surface of the web 53. By this means, any stresses or strains at that portion of the paper 53 which is being cut is completely limited to that portion of the web alone and is not transmitted to any other portion of the web, and thus does not interfere with the motion of the web or with the smoothness of the movement thereof.

The punching mechanism as a whole is mounted on the movable platform 96 for the purpose of permitting the punching plate 109 and the die 126 to travel with the web 53 at the same speed as the web during the cutting operation, that is, during the period that the punching plate is beyond and beneath the upper surface of the web 53. The movable platform is thus so arranged that during the period immediately before the cutting operation is to take place, the entire punching mechanism is in the position shown by the dotted lines of Figure 5; and thereafter, during the cutting operation, the entire punching mechanism travels on its platform 96 to the position shown by the solid lines of Figure 5 and even beyond if necessary, simultaneously making the perforation or incision required and then rising from surface of the web. The web is thus perforated as it travels along and it is not necessary to stop the motion of the web in order to perform the perforating operation. Likewise, the mounting of the punching mechanism on the movable platform 96 is such that immediately after the perforating operation takes place, the entire punching mechanism may be returned to the position shown by the dotted lines of Figure 5 in order that it be ready for the next punching operation.

One form of mechanism by which this oscillatory movement of the platform 96 is accomplished is shown in Figure 2 at 134 and in Figures 5 and 8 and especially Figures 15 and 16. A gear wheel 135 is rotatably mounted on the shaft 61 in such manner that rotation of shaft 61 will not necessarily cause rotation of said gear wheel. A clutch mechanism 600 (Figs. 15 and 16) is so

arranged, however, that a pull on the handle 601 (Figs. 15 and 16) will in a manner hereinafter described cause such gear wheel 135 to rotate with shaft 61. Gear wheel 135 meshes with gear 135a (Fig. 15) thereby driving shaft 61a which through the bevel gears 136 and 137 drives shaft 138 which is rotatably mounted in bearings 139 and 140.

The particular parts of the clutch 600 and the operation thereof as well as the manner in which it serves as a safety device are hereinafter described. The bevel gear 141 mounted at the opposite end of the shaft 138 drives the bevel gear 142 which in turn drives the shaft 143 (see also Fig. 8). The shaft 143 rotates in the bearings 144 and 145, the latter bearing 145 being mounted on the post 146. An arm 147 (see Figs. 5 and 8) is fixedly attached to the opposite end of the rotating shaft 143 and rotates therewith. The said arm 147 (see particularly Fig. 5) has a slot 148 at the free end thereof. A glider 149 is mounted on the end of the arm 147 by means of the shaft 150 and the washer 151, said shaft extending from the glider 149 through the slot 148 and to the washer 151, the edges of the slot 147 being captured between the sides of the glider 149 and the washer 151. The said washer is held in place on its shaft by the nut 152.

It will now be clear that rotation of the shaft 143 as before described, will cause the rotatable arm 147 to rotate and will thus likewise cause the glider 149 to rotate therewith, the glider being free, however, to oscillate within the slot 148.

The shaft 150 extends through the glider 149 to the opposite side thereof into the annular groove 153 (see particularly Fig. 8 as well as Fig. 5) which is formed in the circular plate 154 (see also Figures 12 and 31), said circular plate 154 being supported in fixed unrotatable position by the bar 155 carried by the post 156. The end of the shaft 150 projecting into the annular groove 153 carries, at that portion which rides within said annular groove, a rotatable wheel 157, said rotatable wheel 157 providing a friction reducing bearing surface between the shaft 150 and the sides of the annular groove 153. It will now be clear that as the rotatable arm 147 turns, the glider 149 turns with it but by reason of the freedom allowed to it by its mounting in the slot 148, the said glider in its rotation is free to be guided by the wheel 157 as it rides in the annular groove 153 and thus follows a path given it by the annular groove. A slotted arm 158 is pivotally attached by means of the yoke 159 to the under side of the movable platform 96 at 160, 160. Said slotted arm is also pivoted about the shaft 161 by means hereinafter described.

The lower end of the slotted arm is captured by the glider 149. The glider 149 as seen in Figures 5 and 8, has two rail portions 162, 163 surrounded by the lips 164; the glider 149 rides within the slot 165 of the arm 158, the rails 162 and 163 engaging the sides 166, 166 of the slot 165, the lips 164, 164 capturing the sides 167, 167 between them.

The pivotal mounting of the arm 158 on the shaft 161 above referred to is a slidable one effected by the glider 168. The glider 168 has rails 169, 170 and corresponding lips 171 which cooperate to capture the sides 167 of the movable arm in the same manner as the rails and lips of the glider 149. The glider 168 is free to rotate about the shaft 161 but the shaft 161 is fixedly mounted in its bearings 172, 172 and does not permit any other motion than that of simple rotation by the

glider 168. It will now be clear that rotation of the arm 147 will cause a corresponding rotation of the glider 149. The movement of the glider 149 will be controlled however, not only by the rotatable arm 147 and the slot thereof 148, but also by the path followed by the wheel 157 in the annular groove 153; so that with respect to the rotatable arm and its slot if the annular groove is slightly eccentric, then the glider 149 will slide back and forth in the slot 148.

The rotation of the glider with the rotatable arm 147 and the path followed by the glider owing to the mounting of the wheel 157 in the annular groove 153 will cause a corresponding movement of the lower portion of the slotted arm 158. Thus, when the rotatable arm has rotated from the position shown by the solid lines of Figure 5 through an arc of 180° to the position shown by the dotted lines therein, the lower end of the slotted arm 158 will have been also moved to the position shown by the dotted lines. Since the slotted arm 158 is also pivoted about the glider 168 as a fulcrum then the opposite end of the slotted arm comprising the yoke 159 will have been moved in a direction opposite to that in which the lower end of the slotted arm was moved by the operation of the glider 149. Since the yoke 159 of the slot arm 158 is attached at 160 to the movable platform 96, any motion of the said slotted arm will be transmitted through said yoke and means of attachment to said movable platform and therefore any oscillatory movement of the slotted arm 158 will be reflected by exactly similar movement of the movable platform 96 and corresponding movement of the entire punching mechanism 58. The free mountings comprising slot 165 of the slotted arm 158 and the gliders 149 and 168 are provided, rather than fixed mountings, since the upper end of the slotted arm 158 at 160 is not free to rotate in a circular arc but is required at all times by its attachment to platform 96 to move in a single plane. In order, therefore, to permit such movement of the end of the slotted arm in a single plane while at the same time oscillating such arm about a fulcrum at 168 it is necessary to permit the arm to move relative to said fulcrum. Likewise, the slot 165 and the glider 149 are required since the rotary motion of the arm 147 is to be converted into oscillatory motion of the slotted arm 158 and a sliding of the glider 149 back and forth with respect to the fulcrum of the arm 158 is thereby made necessary.

It is now apparent that rotation of the shaft 143 produces by means of the arm 147 and the slotted arm 158, a corresponding oscillatory movement of the movable platform 96 and of the punching mechanism 58. The speed of oscillation of the movable platform 96 and of the entire punching mechanism 58 may be varied and adjusted by variations in the plate 154 and the annular groove 153 and the distance between perforations or cut-outs made by punching plate upon the moving web 53 may be varied by varying the diameter of the circular plate 154 and the diameter of the annular groove 153 so that the distance covered by the platform 96 during each oscillation of the slotted arm 158 and the corresponding oscillation of the movable platform 96 will be increased or decreased with respect to the moving web 53 and thus space the perforations or cut-outs at a correspondingly different distance from each other. The perforations or cut-outs may thus be placed in series closer to or at a greater distance from each other by a corre-

sponding operation of reducing or increasing the diameter of the circular plate 154. For this purpose, a series of circular plates 154 having varying diameters must be provided.

The necessity for such a series of circular plates may be obviated by another improved expedient associated with the rotatable arm 147 hereinafter to be described.

The movement of the yoke portion 159 of the slotted arm 158 and the corresponding movement of the movable platform 96 may be varied during a single stroke so that the platform will move at the speed of the paper while the punching plate 109 is in contact with the web 53 and at other speeds as may be desired while the punching plate is not in contact with the web 53. This may be accomplished by an eccentricity in the annular groove 153, such eccentricity being placed for instance at 173 (Figs. 5 and 12) and permitting variations in the speed of movement of the wheel 157 by reason of the fact that the effective radius of rotation of said wheel 157 about the shaft 143 will be varied by the forcing of said wheel by the annular groove either closer to the shaft 143 or further away from it. Thus when the wheel 157 is traveling in the portion 173 of the annular groove 153, its speed will be decreased, the decrease of speed being a function of the relationship of the radius at 173 to the radius of the annular groove at other portions thereof. Therefore, while the movable platform 96 is being thrust forward, the speed thereof will be less than that of said platform during the return but will be equal to that of the web 53. Care must however be taken that the formation of the annular groove 153 is such that at all times during the forward thrust of the entire punching mechanism 58, the speed thereof is the same as that of the web 53. The variation in speed of the return of the punching mechanism by reason of the eccentricity of the annular groove 153 thus provides for a resetting of the punching mechanism at the proper time and in the proper place for the next perforating operation.

In a preferred form of activating means for the slotted arm 158, it is possible to omit entirely the circular plate 154 and the annular groove 153. This form is shown in Figures 10, 11, 13 and 14 in which the rotating shaft 143, Figures 10 and 11, which corresponds exactly to the rotating shaft 143 of Figure 8, has mounted at the other end thereof, a rotating arm 174 which corresponds to the rotating arm 147 of Figure 5. The shaft 143' is rotated in exactly the same manner as the shaft 143 of Figure 8 and the rotatable arm 174 securely affixed thereto is likewise rotated thereby.

A glider 175 similar in operation to the glider 149 is pivotally mounted at the end of the rotatable arm 174 and the rails thereof 176, 177 capture the sides 167, 167 of the slotted arm 158 in exactly the same manner. Likewise the pivotal mounting of the oscillating arm 158 about its fulcrum is accomplished by the glider 168 which corresponds to the same member in Figures 5 and 8 and is pivotally mounted on the fixed shaft 161.

The difference between the form thus illustrated in Figures 10 and 11 and that illustrated in Figures 5, 8 and 12 is that the speed of movement of the slotted arm and the corresponding speed of movement of the entire punching mechanism 58 is not varied at any time during the period of operation, said speed being at all times a constant one.

It has been found by experiment that variations in the speed of movement of the punching mechanism, varying its oscillating period, are for most purposes both unnecessary and exceedingly difficult to make; and that it is much simpler to cause the slotted arm and the corresponding platform 96 to move continuously at all times at the same speed as the web 53.

Any variation in the distance between successive perforations or cut-outs may be accomplished by variations in the radius or length of the rotating arm 174 and corresponding changes in the period of the oscillation of the punching mechanism 58.

15 The preferred form shown in Figures 10 and 11 lends itself readily to variations in the speed of oscillation of the punching mechanism 58 without any difficulty or complicated adjustment.

20 Since, as has been above pointed out, the speed of oscillation of the movable platform 96 may be changed by changing the effective radius of rotation of the arm 174 (Figure 10), that is, by bringing the pivoted portion 178 of the glider 175 closer to the shaft 143' or further away therefrom, then any means associated with the rotating arm 174 which will cause said pivoted portion 178 and therefore the glider 175 to move either towards or away from the shaft 143' will be just as effective as changing the length of the rotating arm 174 and will necessarily change the speed of oscillation of the punching mechanism 58.

25 This may be readily accomplished by the apparatus shown in dotted lines in Figure 10 and in the cross-sectional view of Figure 32 wherein (see Figures 13, 14 and 32) the pivoted portion 178 of the glider 175 is secured to a block 179 which is threaded at 180. The block 179 is free

30 to slide within the channel 181 (Figures 13 and 32) of the rotatable arm 174. A block 182 is fixedly secured by means of the bolts 183 (Figures 14 and 32) within the channel 181 and to the body 174 of the rotatable arm. Said block 182

35 is perforated at 184. A bolt 185 having a head 186 is inserted through the perforation 184, its movement relative to the perforation being impeded by the bearings 187 and 188. The opposite end of the bolt 185 is threaded at 189, the

40 threads 189 being so formed as to match exactly with the threads 180. The head 186 of the bolt 185 is so formed as to permit a wrench or tool to capture and turn it. It will now be clear that rotation by a tool of the head 186 will cause a corresponding rotation of the bolt 185 thereby turning the threaded portion 189 thereof which will in turn cause the block 179 to move in a direction corresponding to the direction of rotation and which will thereby move the pivoted portion 178 along the rotatable arm 174 changing its distance from the rotating shaft 143' thus changing the effective radius of rotation between the mounting of the rotatable arm 174 on its shaft and the glider-pivot 178 and the period and speed of oscillation of the movable platform 96 and the punching mechanism 58.

45 It is of course necessary to synchronize the operation of the punching plate 109 of the punching mechanism 58 with the oscillatory movement of the entire punching mechanism. To this end as has been heretofore described, the punching plate 109 is mounted upon a slide 110 which is caused to oscillate by means of the cam 115 (see Figure 8) which rotates with the shaft 113. It

50 55 60 65 70 75 is obviously necessary of course that the down

stroke of the slide 110 of the punching plate 109 be simultaneous with the forward motion of the punching mechanism 58 and should be completed before the return of the punching mechanism 58 commences. It thus becomes extremely useful to drive the punching plate itself from the same source of power that creates the oscillatory movement of the entire punching mechanism 58 and it is desirable to simplify the operation of making any necessary variations in the speed of oscillation of the punching plate 109 when the speed of oscillation of the entire punching mechanism 58 is changed.

Accordingly, the shaft 138 which drives the oscillating mechanism of the entire punching member 58 also drives the shaft 201 by means of the bevel gears 202 and 203, the said shaft rotating in the bearings 204 and 205, the friction upon the shaft being minimized by the thrust bearing 206 (see Figures 2 and 8). The bevel gear 207 at the opposite end of the shaft 201 drives the bevel gear 208 which in turn drives the concentrically arranged gear wheel 209 which, through the idler 210, drives the gear wheel 211 which is mounted on the shaft 212, a spiral gear 213 being mounted also on said shaft 212 (see Figures 2 and 8).

The rotation of shaft 20, therefore, through the gear train 207-211 thereby drives and causes the spiral gear 213 to rotate. The spiral gear 213 and its shaft 212 is mounted in the bearings 214, 214 which in turn are supported on the posts 215, 215 which are fixedly supported by means of the bracket 216 on the frame of the machine so that the spiral member, except for its rotation, has no movement whatsoever with respect to the entire machine and so that the punching mechanism 58 in its oscillation within the machine also oscillates with respect to the mounting of the spiral member 213.

The shaft 113 which operates the punching plate 109 through the cam 115 carries at the end opposite the cam 115 a short spiral gear 217, said short spiral gear being formed to always register with and enter the grooves of the rotating spiral 213. The shaft 113 which operates the punching plate 109 has no motive power other than that transmitted to it through the spirals 213 and 217.

It is essential to so regulate the rotation of the shaft 113 and the corresponding oscillation of the punching plate 109 that any rotation thereof will correspond to the oscillatory movement of the entire punching mechanism 58; that is, that the punching plate 109 will descend through the web 53 during the forward motion of the punching mechanism 58 and so that the punching plate 109 will be free of the web 53 during the return of the punching mechanism.

It is thus found advantageous to cause the rotary motion of the shaft 113 and the corresponding oscillatory motion of the plate 109 to be a function of the oscillatory movement of the entire punching mechanism. Thus as the punching mechanism 58 moves forward, the meshing of the small spiral gear 217 in the spiral 213 causes said spiral gear to rotate and thus causes a corresponding rotation of the shaft 113 and a corresponding oscillation of the punching plate 109.

If the path through which the entire punching mechanism 58 were to pass and if the corresponding path of the spiral gear 217 upon the spiral gear 213 were sufficiently long, then no motion of the spiral gear 213 would be necessary

to create a sufficient rotation of the shaft 113 to effect the punching operation. The motion of the small spiral gear 217 along the spiral gear 213 alone would result in a sufficient rotation to cause the punching plate to rise and fall, and, during the return, a means might then be used to release the spiral gear 217 from its engagement with the spiral 213 in order to prevent any undesired rotation of the shaft 113 in the undesired opposite direction.

However, it is found expedient to cause the spiral gear 213 to rotate, said rotation being preferably at least equal to or greater than the speed which would be induced in the small spiral gear 217 by the return motion of the punching mechanism 58 so that at all times the rotation of the shaft 113 would be in the same direction. Where the speed of rotation of the spiral gear 213 is equal to the speed that would be induced by the return motion of the small spiral 217, then during the return of the punching mechanism 58, the small spiral 217 will merely slide along the groove spiral gear 213 and the shaft 113 and the cam 115 will remain poised in the "up" position so that the punching plate will be free of the web 53 during the return. The rotation of the spiral gear 213 with respect to the small spiral gear 217 also produces another effect and that is that when the forward speed of the punching mechanism 58 and the corresponding forward speed of the worm gear 217 is combined with the additional speed of rotation given to the spiral gear, then the stroke of the cam 115 and the corresponding stroke of the punching plate 109 at the time when it enters and rises from the web is much faster and much more forceful and rapid than would otherwise be the case were there no rotation of the spiral gear 213; and correspondingly, since the effective speed of rotation of the spiral gear 217 during the return of the entire punching mechanism 58 is equal to the difference between the speed of the spiral gear 213 and the speed of the return of the punching mechanism 58, the stroke of the cam 115 along the upper portion of the arc is slower than the downstroke or cutting stroke. Thus, where, in the preferred form, the speed of rotation induced in the small spiral 217 by the return is equal to the speed induced by the rotation of spiral 213. Then during the return of the punching mechanism, the small spiral 217 will simply slide along the groove of the spiral 213, the shaft 113 will not rotate and the cam 115 will consequently be virtually stationary during the return so that the punching plate 109 will be poised in the "up" position during the return.

The punching plate 109 and the die 126 may readily be changed to provide for different sizes and shapes of perforation or cut-out. It should be noted however, that where the same size perforation or cut-out is desired, but where, however, a different space or distance between said perforations is required in order to form bags or articles of different sizes, the only manipulation that is necessary to effect a change in the operation of the machine to increase the said distance is the manipulation or rotation of the head 186 of the bolt 185 (Figure 32) comes in connection with change gear size connected with change of ratio induced by difference in change gear 72. No other operation whatsoever is required for this purpose, except that, as herein-after described, changes in the size of the change gear 72 will produce different speeds of move-

ment of the web 53, thus also assisting in properly spacing the slots or cut-outs from each other.

This means of punching out cut-outs, slots or perforations from a continuous web represents a distinct advance over methods now in use. Heretofore, in many instances it has been necessary where a slot or cut-out or perforation was desired in a sheet which was later to be formed into a bag, to notch the edges of the sheet by means of circular or rotary knives. Thereafter, when the sheet was formed into a bag, container or other article it has been necessary to turn the lateral edges of the sheet to form a seam and at the same time to make sure that the notched portions of the edge of the sheet would exactly register with each other at the seam in order to form the cut-out or window. By use of this method, it was thus not only necessary to effect two cutting operations by two sets of knives on either side of the sheet to be formed but also any inaccuracy in the formation of the container or any lack of exact registration at the seam resulted in distortion or irregularity in the cut-out slotted portion or window. In addition, in the use of said method, where a transparent patch or cover was to be placed over the opening thus formed, great difficulties were encountered since it was necessary to place the patch within the tube thus formed rather than to follow the more simplified operation of placing the patch or transparent cover over an opening in a flat sheet.

Where however, it was previously desired to place a slot, a cut-out or a perforation in the body of a flat sheet or moving web, without halting the web, another known expedient was the use of a series of knives mounted on a circular roller, the rotation of said roller producing the slot or cut-out in the moving web as it passed beneath the roller. The difficulties encountered here comprised the failure of the roller knives to extrude or push out the excised portion of the sheet and the consequent jamming of the roller knives and the difficulties experienced in getting an even, un torn edge around the periphery of the slot.

The use of our punching mechanism herein described provides a simple means for simultaneously punching out all portions of a slot or cut-out in a moving web and at the same time extruding such excised portion from the body of the web and away from the face of the punching plate so that the punching plate is free to make a clean cutting during the next operation.

Also, where knives mounted on cylinders were used and where it was desired to change the distance between the perforations or cut-outs while at the same time maintaining the same size perforation or cut-out, it was necessary to stop the machine and completely remove the cutting cylinder and its associated knives and replace said cylinder with an entirely different one having a greater diameter which would thereby increase the distance between the slots or cut-outs where such increase was desired. By use of our invention herein described, especially in connection with Figure 32, such difficulties are likewise obviated. Many other former difficulties are corrected by the present invention, such advantages and uses being hereafter pointed out where they are not apparent to a person skilled in the art.

Various means may be provided for removing the excised material 127 (see Figure 8) from beneath the punching plate after the cutting operation has taken place. As previously described,

the very operation of punching out the material is sufficient to drop such excised material below the surface of the web 53 and thus prevent its interference with further cutting, punching or other operations. However, rather than permit the excised material 127 to accumulate in the funnel 128 or below the machine, a chute 218 (Figures 2 and 5) is provided immediately beneath the funnel 128 down which the excised material 127 may drop. In order to insure complete removal of the excised material 127 from the funnel 128 through the chute 218, a suction pump 219 (Figures 2 and 3) may be provided which operates to withdraw the air from the chute 218 blowing the exhaust air including the excised material 127 through the tube 220 into the receptacle 221 where vents 222 are provided to permit the exhaust air to escape while nevertheless retaining the cut-out material 127.

After the perforations or cut-outs are formed in the continuous moving web 53, the web travels on to the idling roller 223 (Figures 1 and 2) where its direction is changed, thence it progresses to the idling roller 224 where its direction is again changed, whence it passes beneath the idling roller 225 where once more its direction is changed, whence it passes over the feed roller 226.

The feed roller 226 is driven from the shaft 138A (Figure 2), the bevel gears 227 and 228 causing the vertical shaft 229 to rotate in its bearings 230 and 231, thus causing the bevel gears 232 and 233 to rotate thereby rotating the gear wheel 234 which through the idler 235 causes the gear wheel 236 to rotate, thereby rotating the feed roller 226. The gear wheel 236 also meshes with the gear wheel 237 thereby causing the glueing roller 238 to rotate; and gear wheel 237 meshes with the gear wheel 239 thereby causing the glue roller 240 to rotate (see also Figures 4 and 30).

The glueing roller 238 rides against the glue roller 240, the said glue roller 240 rotating in the glue pot 241, the said glue pot being filled with a liquid adhesive substance. The glueing roller 238 is held against the web 53 and thereby presses it against the feed roller 226 by means substantially the same as that set forth and described with reference to the first feed roller 56. That is, the link 94' and the handles 95' may be rotated as described in connection with the feed roller 56 in order to raise the glueing roller 238 away from the feed roller 226 in the same manner as has been heretofore described in connection with the raising of the rubber roller 11 away from its feed roller 56. This raising means is provided, of course, for the same reason as it was provided in connection with the feed roller 56, that is to facilitate the threading through of the web 53 between the two rollers 226 and 238.

The glueing roller 238 may, of course, have any conformation which may be desired in order to provide an adhesive stripe upon the underlying moving web 53 for the purpose of securing a patch thereon. Thus, the glueing roller 238 may comprise a raised or embossed portion or bead having a conformation slightly larger in its dimensions than the perforation or cut-out, said embossed portion or bead registering with the portion of the web immediately surrounding the cut-out portion and thus providing an adhesive layer at the surface at which the transparent patch or window is to be applied.

Obviously, in order to accommodate varying distances between perforations or cut-outs, that

is where it is desired to change from a sheet adapted to make a small container to one adapted to make a larger one, nevertheless retaining the same size cut-out or opening or where, in any case, it is necessary or desirable to vary the intervals between successive perforations or cut-outs, then the diameters of the feed roller 226 and the glueing roller 238 must be changed in order that the aforementioned interval be increased. This will necessitate the demounting of this roller from its supporting members and the attachment or mounting of a different roller having a circumference exactly equal to the desired distance between successive perforations. Change in the diameter of the roller 238 necessitates the change of the gear wheel ratios throughout the gear train 234-239.

Therefore change gear 235 must be changed in the same way that change gear 72 of the feed rollers 56, 77 must be changed. The operation and utility of such change gears is hereinafter described. It should, of course, be noted that the diameter of feed roller 226 must not be changed since the speed thereof is corrected by change gear 235. Likewise where the diameter of gluing roller 238 is changed, it will be necessary to change the location of the glue roller 240 in order that contact may at all times be made between the glue roller 240 and the glueing roller 238. Accordingly (Figure 2), the base of the glue pot 241 is provided with a rack arrangement 242 and the said glue pot 241 is slidably mounted so that it may slide in a plane parallel to its base. A pinion 243 is rotatably mounted on the small shaft 244, the cogs thereof meshing with the cogs of the rack 242. A handle 245 is secured to the pinion 243 and rotation of the said handle will cause the pinion 243 to rotate, thereby causing the rack 242 to move in the direction of rotation and thereby causing the entire glue pot 241 and the glue roller 240 to move therewith. A set screw 246 may be provided in a slot 247 of the handle 245 so that once the glue pot 241 and its associated glue roller 240 is moved to the desired position, a turning of the set screw against the slot will lock the handle 245 in place, thereby locking the glue roller 240 in place against the glueing roller 238.

Naturally this arrangement of rack, pinion and handle permits the movement of the glue roller 240 out of the way not only for the purpose of permitting it to register accurately with varying sizes of glueing rollers 238, but also facilitates access to the space between the rollers 238 and 226 for threading the web between them and likewise permits adjustment of the glue roller 240 during the operation of the machine to insure that proper pressure is applied between the glue roller 240 and the glueing roller 238.

After the adhesive material has been applied upon the web adjacent the edges of the cut-out or perforations, the web or sheet 53 is moved forward by the feed roller 226 in the same continuous movement to the point 248, (Figures 2, 27, 21, 24, 23) where the patch or transparent sheet is applied over the cut-out to form a transparent window.

A roll 261 of sheet material in the present instance consisting of a roll of transparent regenerated cellulose material is mounted on the shaft 262 (Figure 2) which rotates freely in the bifurcated members 263 which in turn are mounted on the brackets 264 supported by the posts 265 which comprise a part of the framework of the machine. The auxiliary web or transparent sheet

266, is unwound from the roll 261 and carried past the idling roller 267 where it passes between the feed rollers 268 and 269.

The feed rollers 268 and 269 are driven as follows (Figs. 1, 2, 27, 28 and 29): The shaft 270 extending parallel to the shaft 229 and rotating in the bearings 271 is driven by the shaft 229 through the gear wheels 272 and 273. The rotation of the shaft 270 causes the bevel gear 274 to rotate, thereby causing the bevel gear 275 to correspondingly rotate. Bevel gear 275 causes shaft 276 to rotate thus causing elliptical gear 286 to rotate. Elliptical gear 286 meshes with the eccentric gear 285 causing shaft 284 to rotate. Change gear 285a on shaft 284 meshes with idler gear 278. Gear 278 drives gear 279 causing feed roller shaft 269 to rotate. Gear 279 drives gear wheel 280 causing feed roller 268 to rotate.

Variations in the size of change gear 285a will cause variations in the speed of feed rollers 268 and 269 thus causing them to draw more or less of the transparent web through them for each cut thus making longer or shorter patches. This material, as it passes over roll 269 changes direction and passes through guides 281 which direct the transparent web through and between the knife 282 mounted on the cylindrical drum 283 and the steel drum 290.

Knife drum 283 must be regulated so that the knife 282 will always be in the proper position for cutting patches of such length as to register exactly with the cut-out in the web 53. While at the same time, the speed of the knife at the moment of cutting should be the same as the speed of web 266. This regulation of the speed of knife 282 so that its speed at the time of cutting is the same as that of the paper while its speed at other portions of its revolution is faster or slower as may be needed to equal the average speed of rotation imparted to the drum through the shaft 276 is accomplished by making gears 286 and 285 eccentric. Eccentric gears 285 and 286 must always be so enmeshed that the greatest radius of one meets the shortest radius of the other. For variations in length of patch to be cut, the gears must be so turned on their shafts, that the speed of the knife at the time of cutting is the same as that of the web.

The process of utilizing the eccentric gears 285 and 286 to vary the speed will be clearly understood from the following: Shaft 276 drives eccentric gear 286 which drives eccentric gear 285. When knife 282 is in contact with roller 290 the proper position to obtain a long patch is one in which the long radius of eccentric gear 286 is meshed with the short radius of eccentric gear 285. The opposite meshing at the time of cutting, that is of the long radius of eccentric gear 285 with the short radius of 286 will produce a relatively short patch. Other intermediate meshings of eccentric gears 285 and 286 at the moment of cutting will be useful for producing patches of intermediate length.

It is obvious, of course, that where no variation in length of patch or in the speed of transparent web is to be made, then variation in the speed of the knife drum at different points of its rotation will be unnecessary and circular gears rather than eccentricities may be used.

The feed rollers 268 and 269 may be separated in a manner substantially like that shown for feed rollers 56 and 77 to facilitate the threading through of the transparent web.

When the web has been fed by the feed rollers 268 and 269 past said rollers, its direction is

changed and it then passes through the guides 281 to the knife 282 which is mounted on the cylindrical drum 283. The feed roller 268 is so arranged that it may, when desired, be raised away from the roller 269 in order to permit the threading through of the web 266. This may be accomplished in various ways. Thus, the shaft 801 (Fig. 27) supporting the feed roller 268 may have eccentric bushings 803, the shaft 801 fitting into bearing blocks 804 which slide up and down in slots 802 of the side frames. The eccentric bushing is elongated to provide the handle 805 springs between plates 806 and the bearing blocks serve to press the bearing blocks down and hold the feed roller 268 against the roller 269. Rotation of the handle 805 will cause corresponding rotation of eccentric bushing 803, thus causing the blocks 804 to rise against the pressure of the springs previously mentioned and thus raising the roller 268. Release of the handle 805 will cause the springs to force the blocks 804 back thus pressing feed roller 268 against the opposite roller 269. Rotation of the handle in the opposite direction will press the roller 268 even tighter against the roller 269. Top plate 807 is provided with a set screw 808 which may be adjusted to provide a variable stop for the plates 806 and to equalize the pressure of the springs. Set screw 808 may also thus be adjusted to tighten the pressure of roller 268 upon roller 269. The knife 282 and its drum 283 is rotated on the shaft 284 by the gear wheel 285 which meshes with the gear wheel 286 which in turn is rotated by the shaft 276 (see Figure 28). The gear wheel 287 (Figure 28) on the knife shaft 284 meshes with the gear wheel 288 on the shaft 289 which thereby drives the steel roller 290 against which the knife 282 operates.

As the material is fed between the knife drum 283 and the steel roller 290, it is cut by the knife 282 whenever the said knife 282 is revolved about said drum to the line where its edge presses against the transparent web 266 by pressing it against the steel drum 290. A cut is therefore made across the web 266 once during each revolution of the drum 283.

The patch 301 (Figure 27; also Figs. 1 and 2) after it is cut from the web 266 by the knife 282 is then pressed upon the web 53 (Figures 2, 27 and 21) by the rollers 302 and 303. The rollers 302 and 303 are activated by means of a sprocket chain driven by a sprocket 236A concentrically mounted with the gear wheel 236, said sprocket being engaged by the sprocket chain 304 which in turn engaged the sprocket 305; a gear wheel 306 concentrically mounted with the sprocket 305 drives the idler 307 which in turn drives the gear wheel 308 which meshes with the gear wheel 309 (see Figure 29). Since sprocket 236A is mounted on the same shaft as roller 226, then variation in the speed of roller 226 will result in corresponding variations in speed of sprocket 236A. Thus causing corresponding variation in speed of the sprocket 305 which will thus serve to ensure that the rollers 302 and 303 will always be driven at the same speed as roller 226 and thus at the same speed as the web 53. The gear wheel 308 is mounted on the same shaft as the roller 303 and the gear wheel 309 is mounted on the shaft of the roller 302 (see Figure 29); the rollers 303 and 302 being both driven rollers rather than idlers. The mounting of the upper roller 302 may be similar in arrangement to that of the mounting of the other feed rollers 73 and 238, the handle 95" and the link 94" being used to disengage or re-

engage the rollers 302 and 303 in the same manner as hereinbefore described in connection with the rollers 56 and 71.

It is obvious of course, that one end of the patch 301 should be engaged at least by the roller 302 or engaged between the rollers 302 and 303, before the other end of the patch is cut by the knife 282. If the end of the patch is not so engaged before the cut is effected, then the patch 301 may drop down and be utterly valueless and may even clog and disrupt portions of the mechanism.

For this purpose, it is necessary to maintain such exact distances between the knife drum and the portion of it which performs the cutting operation upon the web 266 and the roller 302 or the rollers 302 and 303 that the end of the patch 301 will be engaged and held before the other end is cut from the web 266. For this purpose the entire knife assembly as is seen in Figures 2 and 27 is mounted upon a slidable frame 310, said frame comprising a collar 311 which engages a hollow post 312 rigidly attached to and mounted vertically with respect to the frame of the machine. The collar 311 is slidable with respect to the post 312 and is rigidly attached to the slidable frame 310 by means of the bolts 314, 314. A slot 313 is provided in either side of the hollow post 312 and a bracket 315 extends from the metal frame 310 through the hollow post to the opposite side of the collar 311 and is rigidly attached to both the collar 311 and the sliding frame 310. The center of the bracket is perforated and threaded at 316.

It will now be evident that any upward or downward motion of the bracket 315 will result in a corresponding upward or downward motion of the sliding frame 310 which will likewise result in a raising or lowering of the entire knife mechanism thus permitting adjustment of the distance between the knife edge and the roller 302 in accordance with the varying lengths of patches to be cut. Such sliding upward or downward of the bracket 315 is accomplished by means of the screw 317 (Figures 2 and 27) which is mounted in the hollow post 312. The screw is captured by the bearing 318 at the top of the hollow post 312 and is not free to move longitudinally but is however free to rotate. The portion of the bolt 317 which enters through the threaded perforation 316 of the bracket 315 is threaded in a manner similar to that of the internal threading of the perforation 316 so that any rotation of the bolt 317 will by reason of the fact that the bolt itself is not free to move longitudinally result in the threaded perforation 316 moving along the threads of the bolt 317 thus resulting in a corresponding motion of the bracket 315 and a corresponding motion of the sliding frame 310.

A bevel gear 319 is fixedly attached to the bolt 317 and is rotatable therewith. Said bevel gear 319 meshes with the bevel gear 320 which in turn is rigidly attached to the rotatable shaft 321 to which a handle 322 is rigidly affixed. Rotation of the handle 322 will result in corresponding rotation of the shaft 321 resulting in rotation of the bevel gear 320 causing the bevel gear 319 to rotate, thus causing the screw 317 to rotate, thereby moving the bracket 315 in the sliding frame as hereinbefore described, and raising or lowering the entire cutting mechanism.

In order to insure that the patch 301 is properly gripped between the applying rollers 302 and 303, it may be necessary in proper cases to provide a gripping means which will seize the end of a patch 301 before the patch is cut by

the knife 282 from the web 266, said gripping means being arranged to pass the patch 301 between the rollers 302 and 303 in exactly correct registration with the underlying moving web 53 so that the transparent window may be accurately and properly formed; and further means must be provided in association with the applicating roller or drum 302 which will release the patch 301 from the aforementioned gripping means and which will positively press it away from the roller or applicating drum 302 so that it will be impressed and remain upon the underlying web 53 and thereafter travel thereon. This becomes necessary particularly in view of the fact that any adhesive which may have been applied on the underlying moving web 53 may splay out upon the edges of the overlying patch before said patch is completely free of the applicating roller or the drum 302 and may cause the patch 301 to adhere to the applicating drum or roller 302 in such manner that said patch would tend to be rolled up on said drum rather than be left in its applied position on the underlying web. Therefore, it is essential to provide not merely gripping means to first engage the end of the patch 301 but also a positive releasing or removing means to insure that the patch 301 is completely and accurately removed from its contact with the drum 302.

This function of first gripping the end of the patch 301 as it comes from the cutting apparatus contained in the frame 310 and then releasing the patch and affirmatively pushing it away from its contact with the applicating drum 302 may be accomplished in various ways. A preferred way of accomplishing this is shown specifically in the enlarged view of Figure 22 and the associated views 21 to 26 inclusive all of which figures should be read together with Figures 1, 28 and 27.

The principle which is followed in this modification may generally be understood from the cross sectional diagrammatic illustration in Figures 23 and 24 wherein it may be seen (Fig. 23) that as the patch 301 comes, from the cutting mechanism above, into contact with the applicating drum 302, the end thereof is forced tightly into contact with the face 323 of the drum 302 along the area 324, there being a series of perforations 325 in the face of the drum to which suction is applied in the direction indicated by the arrows 326, such suction being of sufficient force to cause the patch 301 to be held tightly against the applicating drum 302 during its passage along the surface area of the drum 324. The applicating drum is so arranged, in addition, that when the patch 301 (see Figure 24) passes beyond the area 324 and into the area 326 the suction is no longer applied at the perforation 325 in the outer surface of the drum but instead pressure is applied through the very same perforations, and forces the patch 301 away from the surface of the drum 323, causing the patch to continue to adhere to the underlying moving web 53. At all times it should be noted the patch 301 does not move with respect to the surface of the drum but rotates therewith.

When the end of sheet 266 comes in contact with roller 302, it is drawn sufficiently tight against it by the suction. A slight slipping will, however, take place as the roller 302 travels faster than the sheet 266, which is held at feed rollers 268-269 until it is cut off after which such slippage ceases; the patch thereafter travelling at the speed of the roller 302 and of the

main web 53. By this means, the necessity for changing a cylinder is obviated.

Means by which suction and pressure are applied at perforations as they pass along specific segments of the applicating drum are more clearly shown in Figure 22, although Figures 23 to 26 should be studied in connection therewith. A blower 327 (Figure 2) blows air through the tube 328 to the applicating drum 302 (see Figure 22) where the nozzle 329 of the tube 328 is received at one of the mountings 330 of the shaft 331 of the applicating drum 302. Likewise, a suction pump 332 (Figure 2) exhausts the air from the tube 333, the nozzle of which 334 (see Figure 22) is received in the mounting 335 of the shaft 331 at the side opposite the mounting 330.

The circular applicating drum 302 comprises a base or main portion 336, a series of longitudinal grooves 337 surrounding the periphery of the base portion 336 and an outer covering 338 which is affixed to and rotates with the base portion 336 said outer covering having however, a series of perforations 339 which register with the longitudinal grooves 337.

The nozzle 334 of the suction or exhaust tube 333 terminates in a small chamber or tube 340 in the mounting 335. The said chamber or tube communicates with an annular groove 341 in the mounting 335. The main portion 336 of the rotating drum 302 is separated from the mounting by a stationary washer 342 which serves to close the annular groove and prevent any escape of air therethrough except through the slot 343 thereof. The quarter circular slot 343, as is more clearly seen in the cross sectional view of Figure 23, is so arranged that it is continuously adjacent to whatever portion of the outer surface of the applicating drum comprises the area 324 of Figure 23. The slot 343 is also so arranged that the ends 344 of whatever grooves are in line with the said slot are open to said slot and thereby are opened to the annular groove. It will thus be obvious that any air which is exhausted from the tube 333 will be drawn from the tube 340 which in turn will exhaust the air from the annular groove 341 which, through the slot 343, will exhaust the air through the ends 344 of such longitudinal grooves 337 as lie in the area 324 (indicated on Figure 23) or in registration with the slot 343.

By this means, it will be seen that when any portion of the patch 301 (Figures 21 and 23) comes in contact with that part of the outer surface of the drum 302 rotating at any particular moment in the area 324, suction will be applied against that portion of the patch 301 and the patch will be drawn against the outer surface of the drum along such area and will be tightly held thereon while it is being pressed against the underlying web 53.

It will also be obvious that it is necessary only to vary the length of the slot 343 in order to vary the portion of the outer surface of the applicating drum 302 to which suction is applied.

It is also clear that suction is not applied to one specific portion of the drum 302 but is applied to whatever portion of the surface of the drum happens to be in the area 324.

After any portion of the patch 301 has been applied to the underlying moving web 53, it is then necessary to insure that the patch is removed from the drum 302. As is seen in Figure 23, suction terminates at that point where the slot 343 terminates and therefore if the slot ter-

minates along the periphery of the mounting of the drum at that point where the patch 301 is already applied to the underlying web 53, then no further positive attraction is present between the drum and the patch, and the patch should release itself from the drum especially since it is now bound adhesively to the underlying web 53.

However, the patch 301 is made of very light and smooth material and where any irregularities occur in the adhesive stripe, the patch may not be affixed in its proper place on the web 53, but may slide with respect thereto. Also electrostatic attraction may have been set up between the surface of the drum 302 and the patch 301 so that something more than the mere pressure of the feed drum and the application of a not yet dry adhesive may be necessary to insure the prompt removal of every portion of the patch 301 from the drum 302.

In order to accomplish this purpose exactly, the opposite procedure is followed in the area 326 to that followed in the area 324 (see Figure 24). Air is forced under pressure through the tube 328 and the nozzle 329 into the tube or chamber 345 in the mounting or bearing 330. The said tube or chamber 345 communicates with the annular groove 346. The said annular groove 346 is covered and sealed by the fixed washer 347 except at the point where the slot 348 permits air to enter from the annular groove through the slot into the longitudinal grooves 337 and out through the perforations 339.

Since the slot 348 is fixedly arranged in the fixed washer 347 so that its extent corresponds with the peripheral surface area denoted as 326 in Figure 24, it will be obvious that any air which is forced in through the nozzle 329 can escape only through such perforations 339 as communicate with such grooves 337 as are in turn in communication with the slot 348. Thus, at any particular time (see Figure 24) air is forced out only from those perforations lying in that portion of the drum 302 which at the particular moment happens to lie in the segmental area 326; and obviously therefore the patch which might otherwise have, for various reason some of which have been heretofore explained, adhered to the drum 302 after it was intended that it should be associated with the underlying web 53 is forced off the face of the drum by the air pressure through the perforations 339 of that portion of the surface of the drum which at the moment happens to be in area 326.

It will also be clear that such suction is at all times continuous on that portion of the drum which happens to be in area 324 and pressure is continually present at every moment at that portion of the drum which happens at a particular time to be in area 326.

No difficulty can ever arise, therefore, as to the creation of a positive hold upon the patch 301 before it is cut from the web 266 by the knife 282 and a positive release of such patch 301 as it is being applied to the underlying moving web 53.

After the web 53 leaves the drums 302 and 303 between which the patch 301 was applied to said web, it then as it follows path A (which is the path to which the entire foregoing description relates) passes over the idling roller 371 (Figure 2), which changes its direction so that it proceeds towards the base of the machine past the idling rollers 372 and 373 and thence to the roll 374 (see also Figure 4) upon which the com-

pleted web with the series of window formations therein is rolled. The roll 374 mounted on the shaft 375 also acts in part as an additional means for drawing the web of sheet material through the machine.

Shaft 375 carrying roll 374 is driven as follows:

The main drive pulley 60 fixed to shaft 61 drives bevel gear 390 which drives bevel gear 389 which is fixed to and drives shaft 386 which rotates in bearings 387 and 388. Bevel gear 385 at the opposite end of shaft 386 which drives bevel gear 384. Bevel gear 384 and gear 382 are fastened together and rotate on the stationary shaft 383. Gear 382 drives gear 381 which rotates on stationary shaft 380. Gear 381 drives gear 379 by friction through a felt or brake lining washer 392, as hereinafter described.

Gear 379 then drives gear 378 which rotates shaft 375 on its bearings 376 and 377. This shaft rotates roll 374 which is fastened thereon.

The outer end of the shaft 380 at 393 is threaded and a wheel 394 having a spring 395 pressing against collar 395A is mounted on the threaded end 393. Rotation of the wheel 394 will compress spring 395 and cause axial movement of the collar 395A along the shaft 380. This collar presses against thrust bearing 395B which presses against disc 396. A friction clutch comprising the members 396, 396A, a felt or brake lining washer and 397 is mounted on the shaft 380 between the gear wheel 379 and the thrust bearing 395B. The rotation of the wheel or handle 394 will cause the friction clutch 396—397 to operate on the gear wheel 379, 397 being fastened to 379, and will also cause the gear wheel 379 to be pressed against the friction plate 392 the friction plate 392 in turn being pressed against the gear wheel 381. By means of this friction drive, the driven gear wheel 381 will thus cause the gear wheel 379 to rotate thus rotating the gear wheel 378 which in turn will rotate the shaft 375 and wind up the roll 374. The friction plate 392 and the friction clutch 396—397 are provided in order to permit the shaft 375 to slip when extreme tension is applied on the web 53; the friction plate 392 and the friction clutch 396—397 being so adjusted that they will slip under a strain which is less than that which will cause the web 53 to tear.

This is made necessary by the fact that the paper is actually fed through the machine by the feed rollers at a constant speed; as the web 53 is wound up on the roll 374 which also serves in some part to pull the paper through the machine, the diameter of the roll 374 steadily increases and the circumferential speed of the roll is correspondingly increased, thus causing the roll 374 to tend to pull the web 53 at a correspondingly increased speed. Rather than require constant adjustment of the ratios of the gears driving the roll 374, as the diameter thereof increases, it is found far more convenient to permit the roll to slip as the pull exerted by it upon the web is faster than the feeding of the web to it.

And accordingly, by this simplified means, the paper or sheet 53 is wound up on the roll 374 in an even, uniform manner without any danger of the tearing of the web.

When it is necessary, the machine may be conveniently and speedily connected or disconnected from the operating or driving mechanism in order that adjustments may be made without the necessity for going to the inconvenience of stopping the motor or belt which drives the machine. This is accomplished by the manner

in which the belt 59 is mounted on the driving pulley 60 (see specifically Figure 2). The pulley 60 when driven by the belt 59 causes the rotation of the shaft 391 which drives most of the mechanism herein described on the opposite side of the machine and likewise causes the shafts 138 and 138a to rotate through their respective bevel gears. Mounted beside the pulley 60 is an idling pulley 401 which is not connected in any way to any of the shafts of other mechanism of the machine but which is free to rotate concentrically with the pulley 60 and which is of the same diameter as said pulley. It is therefore clear that when the belt 59 is pulled from the pulley 60 over to the idling pulley 401 all of the mechanism of the entire machine except for the blower 219 and the suction pumps 327 and 332 will thereby be disconnected and the belt 59, although still operating on the idling pulley 401 will virtually be completely disconnected from the machine. This disconnecting operation may be conveniently performed by the apparatus shown in Figure 4 wherein the belt 59 is threaded through a sleeve 402 at the end of the shaft 403. The sleeve 402 is so arranged that the belt 59 may move freely therethrough without any undue friction. However, when the shaft 403 is drawn in the direction indicated by the arrow 404 the sleeve 402 will engage one edge of the belt 59 and pull the entire belt over to the idling pulley 401 thus disconnecting the machine. The movement of the shaft 403 in the direction 404 is accomplished by means of the connection of the said shaft 403 at its opposite end to the yoke 405 (see Fig. 1 as well). The yoke 405 is fixedly attached to the shaft 406 (Figures 4 and 1) so that any rotation of the shaft 406 will cause a corresponding rotation of said yoke 405. The end of the shaft 403 is hingedly mounted at 407 (Figure 1) in the yoke 405 so that the yoke 405 will be free to rotate and pull the shaft 403 in any desired direction.

It will thus be clear that rotation of the shaft 406 will cause a corresponding movement of the shaft 403 and thereby cause the belt 59 to be pulled either from the driven pulley 60 to the idling pulley 401 or vice versa. The rotation of the shaft 406 may be accomplished in any convenient manner. One preferred form is shown, however, in Figures 1 and 4 in which each end of the shaft 406 has a bevel gear 408 which meshes with the corresponding bevel gear 409, 409 which are mounted at the end of each of the rotatable shafts 410, 410. The rotatable shafts 410, 410 are free to rotate in their respective bearings 411, 411. The opposite ends of each of the shafts 410, 410 carry a handle 412, 412 the rotation of which will cause the shafts 410 to rotate. The operator of the machine therefore in order to disconnect the entire machine and to stop the operation thereof need merely grasp either handle 412 and rotate it. Rotation of the handle causes rotation of the shaft 410, corresponding rotation of the shaft 406 which thus turns the yoke 405 and draws or pushes the shaft 403 in the desired direction. The mounting of the handle 412 may be marked to indicate the "off" or "on" position.

Various other means may be used throughout the machine in order to improve or facilitate the operation thereof. Thus, for instance, where in order to vary the speed of the feed mechanism in the machine or in order to change spaces between perforations and the lengths of the patch, the size of the applying drum 302 is

changed in any way, the axis of the feed roller 303 may be shifted accordingly with respect to the applying drum 302 so that proper pressure is maintained.

Likewise, where gears of various types in varying locations have their ratio changed with respect to each other, as in the case of change gears, it may be necessary to shift the axial location of such gear wheels and their respective shafts with respect to the gear wheels with which they mesh. For this purpose, pivoted mounting plates 440, 441, 442 are provided at various points throughout the machine (see Figure 1, Figure 29 and Figure 30) where such changes in ratio of gear wheels may be necessary. Thus, where the relative position of the idling gear wheel (Figures 1 and 2) must be changed with respect to the gear wheel 74 and the relative mountings thereof and with respect to the gear wheel 75 and the gear wheel 72, it is obvious that the axial portions of such gears must be changed with respect to each other in order to provide for changes in radius of the gears. Accordingly, the shafts associated with the gear wheels 74 and 73 are carried by the pivoted member 440 which is pivoted at 443 (Figure 1), the said pivoted member 440 having a slot 444 which permits the pivot member not merely to rotate with respect to the pivot 443 but to move into various other positions limited by the slot. It will thus be seen that where the relative diameters of the gear train 72-75 are changed, shifting of the axes of rotation of the gear wheels 74 and 73 to accommodate the changes in diameter will be sufficient to permit the gear train to mesh properly. When the pivoted member 440 has been set with respect to such change in diameter, then a set screw at 443 may be tightened and fixed in that position.

The arrangements for the pivoting members 441 and 442 are in all respects similar and are, as has been pointed out with respect to the pivoted member 440, merely for the purpose of accommodating the respective axial mountings of portions of a gear train to variations in the diameters of the change gears. Thus, the speed of the web 53 through the machine may be varied by variations in the sizes of change gears 72, 234 and 285a, the pivoted mounting of gears 73, 235 and 278 making such change in size possible. Thus a change in size of gear 72 will cause a change in the speed of feed rollers 56 and 57 and a change in speed of the printing rolls. When change gear 73 is changed then gears 234 and 285a must be correspondingly changed so that the speed throughout the machine is the same for all parts. The change gears and the cam 154 of the punching mechanism must also be synchronized and adjusted to each other to properly space the cut-outs or perforations.

It is thus clear from the foregoing description that when the paper is threaded through the machine along the path A, that is through the feed rollers 56 and 57, thence to the punching mechanism 58 thence to the applying drum 302 and thence to the finished roll 374, any other operation which may be performed upon the web must be performed after the completed web has been taken from the finished roll 374. It may be desired, however, to imprint the web 53 either before it is punched or after it is punched and the transparent window applied and before it is received on the finished roll. Such varying operations may be accomplished merely by vari-

ations in the manner in which the web is threaded through the machine. Thus (Figure 2a) the web 53 may be drawn from its roll 50 along the path B in which case it then passes beneath the idling roller 415 thence to the printing rolls or mechanism 416 from which it again returns to the idling roller 417 and thence to the idling roller 54 where its progress through the machine is the same as that for path A. This method of threading is useful where it is desired either to imprint material on the web before the cut out is made or where it may be necessary to mark the material at certain points to facilitate any further process which may be required such as for instance the application of a spot at regular intervals upon the margin of the web 53 in order to guide the photoelectric cell of a cutting or bag-making apparatus which may be required to form the web into a series of bags, envelopes, or sheets.

It may be necessary or desirable however to imprint the web 53 after the transparent window had been formed therein in which case the method of threading of the web 53 through the machine would be slightly different. The sheet 53 would be taken from the roll 50 along the path A past the feed rollers 56, 57 through the punching mechanism 58 past the applicating drum 302 to the roller 371. Thence instead of going directly down towards the base of the machine, that is, towards the roller 372, as was the case in path A, the web 53 will be fed back along the path C to the idling roller 420 thence to the roller 415 whence it would follow path B to the printing mechanism 416 thence along path B to the roller 417 where again its path would diverge from that of path B and it would go directly from the roller 417 past the roller 373 to the finished roll 374.

Other methods of threading the paper through the machine will of course be obvious to those skilled in the art and may be followed as convenience or the requirements of any specific formation may indicate. Likewise, portions of the machine may be rearranged all within the scope of this invention and various parts thereof may take different forms or may be used in combination with other types of apparatus as the occasion may arise.

Various other formations of the apparatus may be desirable, useful or necessary for the proper operation of the machine.

Thus safety means or devices may be provided in order to lessen any danger of injury to the operator and thus to facilitate the use of the machine itself.

When, for instance, the web 53 and the transparent web 266 are threaded through the machine in preparation for the window forming operation, it may be desirable to disconnect the punching mechanism as well as the cutting mechanism from the power or driving means and to ensure that they will remain in such disconnected relation until the operator or user is finished with the threading operation.

While the placement of the driving belt 59, by means herein described, upon the idling pulley 401 is sufficient to disconnect the motive power from the entire machine, nevertheless, for added safety it is found advisable to provide additional disconnecting means for the punching mechanism and the knife which cuts the transparent patches.

Such additional safety device may be provided in the manner shown in Figures 15 and 16.

By the use of this mechanism, the machine may be operated from pulley 61 without driving the punching plate and patch cutting knives and thus facilitating the operation of threading the various webs through the machine.

As previously described, gear 62 on shaft 61 drives gear 63 which through bevel gears 64 and 65 drives shaft 66 which through the gear train 69-75 operates feed rolls 56 and 57 and which 10 through the gears 79 and 80 drives sprocket 500 which thus drives the printing rolls 501 through the sprocket chain 502.

Bevel gear 390 on the opposite end of shaft 61, through the bevel gear 389 drives shaft 386 15 which in a manner previously described drives the wind-up roll 374.

It will thus be clear that by the means thus far described, the web 53 may be threaded through the machine and drawn from the original roll through to the wind-up roll without operating the punching mechanism and without driving the patch cutting mechanism; thus making the threading operation a safe one.

In order to operate the machine in its entirety 25 and to connect the punching mechanism and patch cutting means to the power source, the connecting means or clutch 600 shown in Figures 15 and 16 is provided.

An idling gear 135 (Figure 15) is mounted 30 on shaft 61 adjacent the frame of the machine in such manner that it does not necessarily rotate when shaft 61 rotates. One half 702 of a jaw coupling 703 is fixedly attached to gear 135 and idle therewith.

35 The other half 704 of the jaw coupling is mounted on shaft 61 and is grooved at 705 to receive the key 706 which rotates with shaft 61, so that the half 704 of the jaw coupling rotates with said shaft. The portion 704 is free to move 40 back and forth on the shaft 61, its motion being limited in one direction by the other half 703 of the jaw coupling and in the other direction by the stop 707.

The portion 704 of the jaw coupling also has 45 a peripheral groove 708 arranged to receive the disengaging key 709 which is fixedly mounted on the slide shaft 710. The portion 704 of the jaw coupling is free to rotate part of the disengaging key 709, but any movement of the disengaging key in a plane parallel to the axis of shaft 61 will cause said coupling portion 704, without interfering with its rotation, to move along said shaft. The slide shaft 710 carries a lever 711 the opposite end of which is attached to the push rod 712 which projects outside the frame of the machine and carries a handle 601.

When the handle 601 is pushed toward the frame, the push rod 712 and the lever 711 are 60 correspondingly pushed in. This pushes slide shaft 710 which through the disengaging key 709 pushes coupling part 704 inwardly thus disengaging it from coupling part 702.

When the handle 601 is pulled out, the reverse 65 operation takes place the coupling parts 703 are drawn together and the coupling or clutch is thus engaged, whereby the idling gear 135 is driven.

When idling gear 135 is thus caused to rotate, it drives gear 135a which rotates shaft 61a driving bevel gear 136 which through bevel gear 137 drives the punching mechanism in a manner hereinbefore described.

The handle 601 is maintained in engaging or disengaging position by any suitable means. 75 The release of the clutch by the pushing in of

the handle 601 thus permits the paper to be threaded through the machine and will also permit the paper or web 53 to be drawn through the machine without being punched.

This mechanism thus forms a safety device which will prevent injury to the operator while the web 53 is being threaded through the various portions of the machine in preparation for the punching and window forming operation; and it also permits the web to be drawn through the machine without being punched.

The mechanism herein described, while at first it might seem to be complex, nevertheless provides for an extremely simple and rapid operation by means of which windowed apertures are readily applied to a moving web of material. The material to be thus apertured is mounted in a roll at one end of the machine, threaded past a punching plate which makes the necessary incision without impeding the progress of the web, and is then drawn past the window applying mechanism which also functions without impeding the progress or speed of the web. In the very process of forming the windowed aperture, suitable printing may be applied to the sheet or web either immediately before the perforation or aperture is formed, or after, or the printing step may be omitted.

The provision of a positive hold for the window material as it is at first adjusted by the machine to the apertures of the moving web and then for a positive release for the window material after it is applied, thus insuring that the window forming material will remain in proper contact with and relation to the moving web also insures that the process will function properly.

Many of the individual elements described in the foregoing specification may readily be varied. The arrangement of many of the elements may be changed without changing the essential nature of the invention which relates to the formation of a series of apertures in a moving web and further to the application of suitable window forming material to these apertures. Accordingly, we do not wish to be limited by the specific description herein, but only by the appended claims.

What is claimed is:

1. In an apparatus for making openings in a web of sheet material moving at a constant speed, a punching mechanism; said punching mechanism comprising in combination a punching plate disposed adjacent the surface of said moving web, and a die adjacent the opposite surface thereof; said die being arranged and adapted to receive said punching plate; means for striking said punching plate through said web and into said die; and means for causing said punching plate and die simultaneously to move with said web at the speed of said web during said punching operation; an extruding member yieldingly mounted in the face of said punching plate; said member forcing the punched-out material away from the face of said punching plate when said punching plate strikes through said web; and a receptacle in communication with the opening of said die for receiving the punched-out material.

2. In an apparatus for making openings in a web of sheet material moving at a constant speed, a punching mechanism comprising a platform mounted in a plane parallel to that of the web, means for oscillating said platform in its plane and in a direction longitudinal to that of the web's motion; a punching plate slidably

mounted on said platform and means for oscillating said punching plate in a plane substantially normal to that of the web, said means comprising a cam mounted on a shaft, a link connecting said cam and said punching plate, a worm gear at the end of said shaft enmeshed with a spiral gear stationarily mounted independently of the punching platform; the oscillation of said platform causing said worm gear to rotate in said spiral and thus causing said punching plate to oscillate.

3. In an apparatus for making openings in a web of sheet material moving at a constant speed, a punching mechanism; said pushing mechanism comprising in combination a punching plate disposed adjacent one surface of said moving web, and a die adjacent the opposite surface thereof; said die being arranged and adapted to receive said punching plate; means for striking said punching plate through said web and into said die; and means for causing said punching mechanism including said punching plate and die to oscillate in a plane parallel to that of the web; and, during the time that the punching plate is struck through said web, to move with said web in the same direction and at the same speed as the web, said means comprising an arm hingedly attached to said punching mechanism, said arm being slidably mounted on a fulcrum, and means for swinging said arm about said fulcrum.

4. In an apparatus for making openings in a web of sheet material moving at a constant speed, a punching mechanism; said punching mechanism comprising in combination a punching plate disposed adjacent one surface of said moving web, and a die adjacent the opposite surface thereof; said die being arranged and adapted to receive said punching plate; means for striking said punching plate through said web and into said die; and means for causing said punching mechanism including said punching plate and die to oscillate in a plane parallel to that of the web; and, during the time that the punching plate is struck through said web, to move with said web in the same direction and at the same speed as the web, said means comprising an arm hingedly attached to said punching mechanism, said arm being slidably mounted on a fulcrum, and means for swinging said arm about said fulcrum, said last mentioned means comprising a rotatable member, the end of said member being slidably captured by said arm, and means for adjusting the effective radius of said rotatable member for varying the swing of said arm.

5. In an apparatus for making openings in a web of sheet material moving at a constant speed, a punching mechanism; said punching mechanism comprising in combination a punching plate disposed adjacent one surface of said moving web, and a die adjacent the opposite surface thereof; said die being arranged and adapted to receive said punching plate; means for striking said punching plate through said web and into said die; and means for causing said punching plate and die simultaneously to move with said web at the speed of said web during said punching operation; a receptacle in communication with the opening of said die for receiving the punched out material; and a suction pump for withdrawing all of said punched out material from said die and for depositing said material in said receptacle.

6. In an apparatus for making openings in a web of sheet material moving at a constant speed,

a punching mechanism comprising a platform mounted in a plane parallel to that of the web; means for oscillating said platform in its plane and in a direction longitudinal to that of the motion of the web; a punching plate slidably mounted on said platform and means for oscillating said punching plate in a plane substantially normal to that of the web, said means comprising a cam mounted on a shaft, a link connecting said cam and said punching plate, a small spiral gear at the end of said shaft enmeshed with a spiral gear stationarily mounted independently of the punching platform; the oscillation of said platform causing said spiral gear to rotate in said spiral and thus causing said punching plate to oscillate; and means for rotating said spiral gear in its stationary mounting at a speed greater than that induced in the spiral gear during the return movement of the platform whereby said spiral gear is continuously rotated in a single rotary direction.

7. In an apparatus for making openings in a web of sheet materials moving at a constant speed, a punching mechanism; said punching mechanism comprising in combination a punching plate disposed adjacent one surface on said moving web, and a die adjacent the opposite surface thereof; said die being arranged and adapted to receive said punching plate; means for striking said punching plate through said web and into said die; and means for causing said punching mechanism including said punching plate and die to oscillate in a plane parallel to that of the web; and, during the time that the punching plate is struck through the web, to move with said web in the same direction and at the same

speed as the web, said means comprising an arm hingedly attached to said punching mechanism, said arm being slidably mounted on a fulcrum, and means for swinging said arm about said fulcrum, said last mentioned means comprising a rotatable member the end of said member being slidably captured by said arm.

8. In an apparatus for making openings in a web of sheet materials moving at a constant speed, a punching mechanism; said punching mechanism comprising in combination a punching plate disposed adjacent one surface on said moving web, and a die adjacent the opposite surface thereof; said die being arranged and adapted to receive said punching plate; means for striking said punching plate through said web and into said die; and means for causing said punching mechanism including said punching plate and die to oscillate in a plane parallel to that of the web; and, during the time that the punching plate is struck through the web, to move with said web in the same direction and at the same speed as the web, said means comprising an arm hingedly attached to said punching mechanism, said arm being slidably mounted on a fulcrum, and means for swinging said arm about said fulcrum, said last mentioned means comprising a rotatable member the end of said member being slidably captured by said arm, and means for varying the effective radius of said rotatable member during a single rotation for varying the speed of said arm during each swing.
